UNITED STATES PATENT OFFICE.

JOHN ANTHONY HONEGGER, OF NEW YORK, N. Y.

SMOKING SET.

Application filed August 8, 1924. Serial No. 730,958.

To all whom it may concern:

Be it known that I, JOHN A. HONEGGER, a citizen of the United States, and resident of the city of New York, borough of Queens, 5 in the county of Queens and State of New York, have invented a new and Improved Smoking Set, of which the following is a full, clear, and exact description.

This invention has relation to receptacles 10 and has particular reference to a combination smoking receptacle for use primarily in connection with automobiles or other vehicles or when associated with a suitable supporting element as a table smoking set.

One of the outstanding objects of the 15 present invention is to provide a combined receptacle for a package of cigarettes, a package of book matches and for smoking refuse, which facilitates the insertion and removal of said elements.

As a further object the invention comprehends a combined receptacle of the character set forth in which the several parts thereof are capable of being stamped from 20 sheet material and bent upon themselves whereby the device may be cheaply constructed and assembled.

With the above recited and other objects in view, the invention resides in the novel 25 construction set forth in the following specification, particularly pointed out in the appended claims and illustrated in the accompanying drawings, it being understood that the right is reserved to embodiments 30 other than those actually illustrated herein, to the full extent indicated by the general meaning of the terms in which the claims are expressed.

In the drawings—

40 Figure 1 is a perspective view of the completed device ready for association with the dashboard of a vehicle;

Fig. 2 is a front elevation thereof;

Fig. 3 is a vertical sectional view therethrough taken approximately on the line 45 3-3 of Fig. 2;

Fig. 4 is a top plan view thereof;

Fig. 5 is a plan view of the blank which constitutes the rear wall of the device;

50 Fig. 6 is a plan view of the blank which constitutes the front and side walls of the device;

Fig. 7 is a plan view of the blank which constitutes the refuse tray cover;

55 Fig. 8 is a perspective view of the holder

or supporting stand which adapts the device for table use;

Fig. 9 is a vertical sectional view therethrough with the device illustrated in dotted lines in supported relation therewith.

Referring to the drawings by characters of reference the combined receptacle includes a rectangular body 10 having a forwardly and downwardly inclined lower end 11 and an open upper end which is closed by a cover 12. The cover 12 is hinged at 13 to the rear edge of the upper open end and is normally moved to a closed position with respect thereto by means of a spring 14. A hollow carrier member 15 of a size 60 16 and configuration to receive a cigarette package is mounted within the body 10 for vertical movement and said carrier member is provided with a bottom wall 16. A transverse cam shaft 17 is journaled in the side 65 walls of the body 10 below the bottom wall 16 of the carrier member and a lifting and lowering cam 18 is secured to the cam shaft 17 for operative engagement with the bottom wall 16 to effect the raising and lowering of 70 the package carrier 15 upon rotation of the cam and cam shaft. One end of the cam shaft which protrudes beyond the side wall of the body 10 is bent radially to provide a manipulating arm or handle 19 for the 75 purpose of rotating the shaft and cam. The side walls of the carrier element 15 at the upper end are provided with upwardly projecting extensions 20 having rounded or semi-circular upper edges 21 which cooperate with the underside of the cover 12 upon upward movement of the carrier member to effect the swinging of said cover to opened 80 position against the action of the spring 14. The front wall 22 of the body 10 has 85 its lower edge terminating slightly above the upper edges of the side walls 23 of the forwardly and downwardly inclined lower end 11 of the body and the said lower edge of the front wall 22 is provided with a forwardly projecting central lug 24. The front wall 22 is further provided adjacent its lower edge with transversely spaced outstruck tongues 25 and said tongues together 90 with the lug 24 define a means for receiving and holding a package of book matches. The rear wall 26 of the body 10 is provided with laterally projecting rearwardly offset ears 27 having upwardly extending slots 28 95 from their lower edges to engage over 100

110

headed supporting elements provided in the dashboard of a vehicle when the device is employed in this capacity. The lower end 11 of the body 10 which is defined by the 5 forwardly and downwardly inclined lower extremity 29 of the rear wall 26 and by the angular terminals 30 of the side walls 23 of the body 10 constitutes a smoking refuse compartment for ashes, burnt matches or 10 cigar and cigarette stumps.

In order to provide means for closing the forward end and upper portion of the refuse compartment, while at the same time to permit of the removal or discharge of the 15 refuse, a pivoted member designated generally at 32 is provided which consists of angularly disposed walls 33 and 34, the latter being provided with laterally projecting journals or trunnions 35 on its opposite edges 20 which are mounted in bearing openings 36 in the walls 30. The upper wall 34 is further provided with an upwardly projecting angular flange 37 which is designed when the member 32 is in closed relation, to engage 25 behind the lower edge of the front wall 22. The end wall 33 of the device 32 is provided with rearwardly bent side flanges 38 which embrace the sides of the forward edges of the walls 30 and the lower edge of 30 the front closure wall 33 is provided with a central resilient rearwardly projecting clip 39 which is designed to frictionally engage under the forward edge of the bottom wall 29 of the refuse compartment. The 35 walls 33 and 34 are provided with a cut-away portion 40 defining an opening whereby access may be gained to the refuse compartment for disposing the refuse therein and the lower edge of the material defining 40 the opening 40 is provided with a forwardly projecting arcuate lip 41 to constitute a cigar or cigarette rest.

In order to illustrate the manner in which the device is constructed the blank A from 45 which the back or rear wall 26 is constructed is shown in Fig. 5; the blank B from which the front and side walls 22 and 23 are constructed is shown in Fig. 6; and the blank C from which the refuse compartment covering means is constructed is shown in Fig. 50 7. Referring to the blank A it will be noted that adjacent its longitudinal or side edges a line of slots 42 is provided while the rear edges of the side walls 23 and the angular terminals 30 thereof are provided with 55 tongues 43 which are inserted through the slots 42 and bent laterally to hold the device in assembled relation. The side walls 23 and their angular terminals 30 are bent along 60 the lines indicated at 44 in Fig. 6 after which the lower portion 29 of the rear wall 26 is bent along the line 45 to snugly fit against the lower edges of the angular terminals 30. The upper edge of the rear wall 26 is provided 65 with spaced integral lugs 46 which are

bent around to provide the hinge knuckles for receiving the hinge pin 13 when brought into alignment with the complementary hinge knuckles 47 on the cover 12.

When it is desired to use the device as a 70 table smoking set, a supporting stand or holder 50 illustrated in Figs. 8 and 9 is employed and said stand consists of a single length of sheet material which is bent upon itself to provide a vertical wall 51 having 75 laterally projecting ears 52 adjacent its upper end by which headed elements 53 are carried. The lower end of the vertical wall 51 is bent laterally as at 54 and thence forwardly as at 55. The side edges of the forwardly bent portion 55 are provided with upstanding flanges 56 having inturned rear edges 57 which lie behind the lower portion of the vertical wall 51. This construction constitutes a base for the vertical wall having side flanges 56 so that the slotted portion 28 of the arms 27 may engage over the headed elements 53 as illustrated in Fig. 9 with the side walls of the refuse compartment maintained between the flanges 56. 80

In use of the device, the handle 19 is manipulated to turn the cam and cam shaft which effects a lifting and upward movement of the carrier element 15. A package of cigarettes is then inserted in the carrier 95 element which is lowered into place by the handle 19, the spring 14 functioning to close the cover 12. The package of book matches with the cover flap torn away is inserted between the tongues 25 with the lower edge 100 resting upon the lug 24 and the abrasive or scratching surface thereof lying between the lower edges of the tongues 25 and the lug 24. A cigarette or cigar may be inserted upon the lip 41 which is designed for this purpose and the ashes, burnt matches, cigar or cigarette stumps are introduced to the refuse compartment through the opening 40. When it is desired to empty or discharge 110 the refuse from said compartment, the operator swings the member 32 on its trunnions or journals 35 to the position illustrated in dotted lines in Fig. 3. It will be noted that the flange 37 of the element 32 serves to engage behind and assist in displacing the refuse from its compartment. It will be further noted that the cam 18 engages with the rear wall 26 which serves as a stop for the cam whereby the cam in turn limits the 115 downward movement of the carrier 15.

From the foregoing it will thus be observed that an extremely simple and inexpensive smoking set has been devised which is primarily designed for association with the dashboard of an automobile and the construction and arrangement of the same is such as to dispose the compartments in vertical alignment in order that the width of the device is reduced to a minimum. 125

I claim:

1. A smoking set comprising a receptacle body having super-posed compartments for the reception of book matches, cigarettes and smoking refuse, the cigarette compartment having an open upper end, a vertically shiftable package carrier in said compartment, and means for manually shifting said carrier upwardly to facilitate the insertion or removal of the cigarette package or the withdrawal of the cigarettes therefrom, said receptacle body having laterally projecting rearwardly offset slotted ears for removably attaching the device to suitable supporting elements in combination with a supporting stand including a vertical wall, a base at its lower end and side flanges on the base between which the lower end of the receptacle body is positioned.
2. A combined receptacle for cigarettes, book matches and smoking refuse comprising a vertically disposed rectangular body having an open upper end, a forwardly and downwardly inclined lower end defining a smoking refuse compartment, a cigarette carrier element mounted within the body for vertical movements, manually operable cam means extending through the body for effecting upward movement of said carrier to project the upper end of the cigarette package from the upper open end of the body whereby to facilitate the insertion or removal of the package or the withdrawal of the cigarettes therefrom, and means formed on the front wall of said body for receiving and holding a package of book matches.
3. A combined receptacle for cigarettes, book matches and smoking refuse comprising a vertically disposed rectangular body having an open upper end, a hinged cover therefor normally moved to a closed relation, a forwardly and downwardly inclined lower end of said body defining a smoking refuse compartment, a cigarette carrier element mounted within the body for vertical movements, manually operable cam means extending through the body for effecting upward movement of said carrier element to project the upper end of the cigarette package from the upper open end of the body to facilitate the insertion or removal of the package or the withdrawal of cigarettes therefrom, means on the carrier element engageable with the cover upon upward movement of said element for swinging the cover to open position, and means formed on the front wall of said body for receiving and holding a package of book matches.
4. A combined receptacle for cigarettes, book matches and smoking refuse comprising a vertically disposed rectangular body having an open upper end, a forwardly and downwardly inclined lower end defining a smoking refuse compartment, a cigarette carrier element mounted within the body for vertical movements, manually operable cam means extending through the body for effecting upward movement of said carrier to project the upper end of the cigarette package from the upper open end of the body, said means for receiving and holding a package of book matches, a transverse cam shaft journaled in the side walls of the body having an exteriorly disposed laterally bent end serving as a handle, a cam secured to said shaft and operatively engaging the lower wall of the carrier element to constitute means for effecting upward movement of said carrier to project the upper end of the cigarette package from the upper open end of the body and for supporting said carrier element respectively in its raised or lowered positions.
5. A combined receptacle for cigarettes, book matches and smoking refuse comprising a vertically disposed rectangular body having an open upper end, means formed on the front wall of said body for receiving and holding a package of book matches, a cigarette carrier element mounted within the body for vertical movements, means for manually effecting the upward movement of said carrier to project the upper end of the cigarette package from the upper open end of the body, said means serving to support the receptacle in its raised or lowered positions, and a forwardly and downwardly inclined lower end of said body defining a smoking refuse compartment, and a closure member for said latter compartment fulcrumed thereto and having a terminal for effecting the discharge of the refuse therefrom upon opening of said closure.
6. A combined receptacle for cigarettes, book matches and smoking refuse comprising a vertically disposed rectangular body having an open upper end, means formed on the front wall of said body for receiving and holding a package of book matches, a cigarette carrier element mounted within the body for vertical movements, means for manually effecting the upward movement of said carrier to project the upper end of the cigarette package from the upper open end of the body, said means serving to support the receptacle in its raised or lowered positions, and a forwardly and downwardly inclined lower end of said body defining a smoking refuse compartment, and a closure member for said latter compartment fulcrumed thereto and having a terminal for effecting the discharge of the refuse therefrom upon opening of said closure, said closure member having an opening for inserting the refuse and provided with a supporting lip for cigars or cigarettes.

JOHN ANTHONY HONEGGER.
